US0D1100881S

(12) **United States Design Patent** (10) Patent No.: **US D1,100,881 S**
(45) Date of Patent: ** Nov. 4, 2025

(54) **HEADPHONE**

(71) Applicant: **SONOS, INC.**, Goleta, CA (US)

(72) Inventors: **Sam Prentice**, Santa Barbara, CA (US); **David Keating**, Glasgow (GB); **Jo-Yun Wang**, Glasgow (GB); **Matthew Innes**, Glasgow (GB); **Alexia Delhoume**, Boston, MA (US); **Tristan Taylor**, Boston, MA (US); **Roderick George William Philip**, Inverness (GB); **Aki Laine**, Santa Barbara, CA (US); **Francesca Alyssum Quaglia**, New York, NY (US)

(73) Assignee: **SONOS, INC.**, Goleta, CA (US)

(**) Term: **15 Years**

(21) Appl. No.: **30/006,770**

(22) Filed: **Jun. 4, 2025**

Related U.S. Application Data

(63) Continuation of application No. 29/975,863, filed on Dec. 2, 2024, now Pat. No. Des. 1,082,744, which is a continuation of application No. 29/873,484, filed on Mar. 31, 2023, now Pat. No. Des. 1,059,327.

(57) **CLAIM**

The ornamental design for a headphone as shown and described.

DESCRIPTION

FIG. 1 is a perspective view of a headphone.

FIG. 2 is second perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the headphone that form no part of the claimed design.

1 Claim, 7 Drawing Sheets
